UNITED STATES PATENT OFFICE.

JOHN McE. AMES, OF DONGAN HILLS, NEW YORK.

CAR-BOLSTER.

1,021,733.

Specification of Letters Patent. Patented Mar. 26, 1912.

Application filed October 26, 1911. Serial No. 656,827.

To all whom it may concern:

Be it known that I, JOHN McE. AMES, residing at Dongan Hills, Staten Island, New York, and being a citizen of the United States, have invented certain new and useful Improvements in Car-Bolsters, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an elevational view of the bolster. Fig. 2 is a plan view. Fig. 3 is an end view. Fig. 4 is a sectional view, the section being taken on line 4—4 of Fig. 1.

The object of the invention is to provide a simple, strong and light cast bolster especially adapted for tank car service, in the construction of which car side sills are omitted, the bolster extending at its base outwardly to combine therewith side bearings and at the top to form a tank cradle of sufficient length to properly support tanks up to 10,000 gallons capacity or over, a feature of the invention being the omission of the greater portion of the vertical bolster web in the vicinity of the center sills of the car so as to permit of considerable transverse and rotative movement of such sills when being applied and connected with the bolster, as well as to provide a wide gap between said sills and the bolster web, when the sills are in position, so as to permit ready manipulation of riveting tools used to rivet the sills and bolster together. To that end the bolster shown is a single casting comprising integral top and bottom connecting plates between which are the vertically disposed sill attaching flanges (so called) and beyond these flanges come the sill gaps, while beyond said sill gaps are provided triangular extensions which, along their upper faces, receive wood filler blocks upon which rests the tank and said triangles terminate at their lower angles in bolster side bearings

adapted to coöperate with the usual side bearings carried by the car trucks.

Referring to the parts, 1 is the bottom plate which is wider near its middle portion than near the ends and is provided at its middle portion with a center bearing extension 2 adapted to coöperate with the center bearing plate usually carried by the truck.

3—3 are longitudinally extending flanges which project downwardly and outwardly from the plate 1 and serve as reinforcing flanges.

Disposed centrally above the plate 1 is a pin socket 4 which is connected by a vertical web 5 with what are herein called sill attaching flanges 6, said flanges comprising vertical walls which extend from the bottom plate 1 to the top plate 7 of the bolster, the usual pin gap 8^a being provided in the web 5 between the sill flanges 6. The bottom plate 1 beyond the flanges 3 is provided with laterally extending flanges 8, which curve upwardly to near the vicinity of the obliquely disposed ribs 9, thence downwardly and outwardly in relatively horizontal lines to form the side bearings 10.

Extending inwardly from the top and bottom plates and the ribs 9 are bolster webs 11 which terminate a considerable distance from the sill flanges 6, before referred to, thus providing sill gaps which are wide enough to permit of projecting the sills through said sill gaps while said sills are in horizontal position; then rotating such sills to vertical position; that is, with the webs of the sills in contact with the sill attaching flanges 6. Between the top and bottom inner ends of these flanges 11 the inner face of the top and bottom bolster plates 1—7 are preferably flattened, as shown in Fig. 1, so as to provide a wide flat bearing upon which may rest the supporting sills of the car during the time the underframe parts are being assembled and after the sills are riveted in position to the flanges 6. The gaps 12 thus provided between the top and bottom bolster plates, the flanges 6 and the webs 11 are of sufficient extent to permit ready insertion of sills being projected through said gaps while said center sills are provided with draft lugs and such appurtenances as are commonly connected with center sills in tank cars, and

- the gaps extend sufficiently to permit the sills being projected through said gaps while the sills are horizontally and obliquely disposed, after which the sills may be placed 5 in vertical position upon the sill seats 1^a and moved inwardly into contact with the flanges 6, to which flanges said sills are secured by rivet connection, the gaps 12 being large enough to pass the riveting tools used 10 to secure the sills in position through said gaps, thus permitting the use of pneumatic or other riveting tools and materially reducing the cost of assembling the underframe parts.
- 15 The top bolster plate 7 is, as shown in Fig. 1, flat or provided with horizontally projecting flanges 13 throughout its middle portion and rises obliquely upwardly to provide seats for the wood blocks 14 which are 20 shown in position in Fig. 1 and in the left hand portions of Fig. 2.
- The top plate is provided with longitudinally extending strengthening ribs 15 which 25 extend outwardly from the vicinity of the sill flanges 6 and extend slightly beyond the ribs 9, thereby providing side walls for the inner ends of the wood blocks 14, before referred to. This top bolster plate is reinforced also by means of a thickened portion 30 16 which is deepest above the bolster webs 11 and gradually decreases in thickness, as shown in the sectional view Fig. 4, disappearing in the flanges 13 at or near the outward extremities of said flanges above the 35 middle portion of the bolster and this thickened portion sharply converges, as shown in the plan view Fig. 2, terminating near its outer ends in inclined seats 17, against which seats rest the inner ends of the wood blocks 40 14. Thus the wood blocks 14 are held in position at their inner ends by contact with the abutments 17 and by the vertical flanges 15, while the outer end portions of said 45 wood blocks are recessed and fit over the integral studs 18 which extend above the top plate portions 7^a as best shown in Figs. 1 and 2. Beyond the studs 18 the bolster is bifurcated, as best shown in the plan view 50 Fig. 2, and perforations 19 extend through the bifurcated portion of the bolster. This bifurcation is provided so as to permit connecting with the bolster yokes adapted to receive either the lower ends of tank bands 55 commonly used in tank cars, or as means for supporting running boards, but as this invention relates solely to the bolster, such connections are not shown.
- Extending obliquely downwardly from 60 the bifurcated outer ends of the bolster are ribs 20 which, with the oblique ribs 9 and the oblique extensions 7^a of the top bolster plate, form triangles terminating at their base in the side bearings 10 before referred to, and between these ribs is a web portion 65 21 which projects inwardly, as best shown

in Fig. 1. Projecting outwardly and downwardly from the oblique ribs 20 are lugs 22 which are preferably perforated and serve as supports for means adapted to support running boards not shown.

By the term "plate" as here used I do not mean to indicate a separately formed sheet metal plate commonly used as a bolster cover plate, but refer generally to the somewhat flattened top and bottom bolster portions cast integral with and which serve as connectors for the laterally extending triangular parts indicated.

The bolster designed for service is intended to be used with channel center sills and assuming said sills to be 13" channels the gaps 12 would be more than 13" across at their longest measurement so as to permit the sills to be turned on their sides and manipulated as may be necessary to pass 85 through the said gaps.

What I claim is:

1. In an integral cast bolster, a plurality of relatively triangular flanged portions terminating in side bearings, a connecting bottom portion comprising a pin socket and sill attaching flanges and a continuous top portion provided with timber retaining means.

2. A tank car bolster comprising an integral casting, having triangular upwardly extending portions terminating in side bearings at their lower ends and in tank supports at their upper portions, top and bottom connecting portions, an intermediate center pin socket and sill attaching flanges and having enlarged sill gaps between said portions.

3. A tank car bolster comprising an integral casting, having inwardly flanged triangular upwardly extending portions terminating in side bearings at their lower ends and in tank supports at their upper portions, top and bottom connecting portions, an intermediate center pin socket and sill attaching flanges, and having enlarged sill gaps between said portions.

4. A tank car bolster comprising an integral casting, having triangular upwardly extending portions terminating in side bearings at their lower ends and in tank supports at their upper portions, longitudinally flanged top and bottom connecting portions, an intermediate center pin socket and sill attaching flanges, and having enlarged sill gaps between said portions.

5. A tank car bolster comprising an integral casting, with spaced vertical web portions, triangularly disposed flanges extending from said webs, a bottom connecting portion provided with center bearing, the top connecting portion being provided with longitudinally disposed flanges and abutments adapted to retain a superposed member in position, and sill attaching flanges.

connecting said top and bottom connecting portions.

6. In a tank car bolster, an integral casting combining top and bottom portions, laterally extending triangular cradle extensions, terminating at their bottom angles in side bearings and being connected by said top and bottom portions, an intervening center pin socket with flanges extending therefrom, sill connection flanges at the ends of

said first mentioned flanges, and flanges and abutments on the upper face of said bolster adapted to retain longitudinally extending blocks in position.

In witness whereof I have hereunto set my hand in the presence of two witnesses.

JOHN McE. AMES.
